ROY CROSS, OF KANSAS CITY, MISSOURI.

METHOD IN THE TREATMENT AND REFINING OF PETROLEUM.

1,255,138.

Specification of Letters Patent. Patented Feb. 5, 1918.

Application filed January 8, 1917. Serial No. 141,294.

To all whom it may concern:

Be it known that I, Roy Cross, residing at Kansas City, in the county of Jackson and State of Missouri, have invented certain new and useful Methods in the Treatment and Refining of Petroleum, of which the following is a specification.

My invention relates to a process for treating and refining petroleum which has for its object the simultaneous transformation of heavy hydrocarbons into light hydrocarbons and the distillation of the light hydrocarbons without the use of a reflux condenser and without distilling the heavy hydrocarbons.

In the methods now in use for the transformation of heavy hydrocarbons into light hydrocarbons with simultaneous distillation there is, on account of the high temperature required, an undesirable quantity of heavy hydrocarbons carried over in the vapor form and these must be separated from the light hydrocarbons by a subsequent treatment.

When, in order to prevent their distillation, the vapors of the heavy hydrocarbons are passed into a condenser cooled sufficiently to allow only the light hydrocarbons to pass through, there is an abstraction of a large amount of heat which retards very much the rate of transformation of the heavy hydrocarbons as well as very greatly increases the total amount of heat required for the treatment.

By the method of the present invention, the heavy hydrocarbon vapors do not pass from the container since they are readily condensed and absorbed by the cooler incoming hydrocarbons not yet under treatment and the incoming hydrocarbons are sufficiently heated to materially lessen the time of treatment required to later transform them into light hydrocarbons.

The essence of this invention is that in the cracking and distillation of petroleum, the hydrocarbon vapors arising from the heavy hydrocarbons under transformation shall pass into contact with a body of cooler heavy hydrocarbons sufficient in volume to replace the body of hydrocarbons under treatment but later to be treated and under the same pressure as the portion of the hydrocarbons under treatment. The accompanying drawing shows a means for the practice of this invention.

Heavy petroleum oil is introduced from a supply line 1 into the container 5 through a pipe 4 by means of the pump 2 until the

containers 5 and 6 are half full, the valves 9 and 10 in the connecting pipes 7 and 8 being open. Then the pump 2 is stopped, the valves 11, 9, 10, 13, 3 and 26 are closed and heat is applied to the pipes 16 carrying the oil to and from container 6 which acts as a vapor container and vapor exit means and not as a container for a bulk of supply oil. The oil is made to circulate by means of the pump 8' through pipe 12 into pipes 16 in furnace 17 and back into container 6 through inlet pipe 18. Then a pressure of 600 pounds per square inch, more or less, is allowed to develop as shown by gage 19 and a temperature of between 300° C. and 450° C. as shown by thermometer 20. The actual operation as to pressure and temperature will vary depending upon the character of the heavy hydrocarbons under treatment and upon the end boiling point of the product desired. Valve 9 is now opened slowly allowing the pressure to gradually develop in container 5 as shown by gage 21, being fully open when the pressure in container 5 is equal to the pressure in container 6. Valve 11 is now opened but not sufficiently to allow any considerable change in pressure or temperature in container 6 as shown by gage 19 and thermometer 20. When the temperature of the oil in 5 as indicated by thermometer 22 tends to exceed the end boiling point of the light hydrocarbons desired, pump 2 is started, the cold oil is introduced through pipe 4 with valve 8 open until the temperature is reduced to the proper point. Valve 13 in pipe 14 may be opened, valve 15 closed and pump 8' operated to remove sludge as frequently as required by the accumulation of carbon or semi-solid matter. With proper regulation, the treatment goes on continuously without operation of valves, the body of heavy oil in 5 being kept at a temperature such that light hydrocarbons of a desired volatility go forward to the condenser while heavier are taken up in the heavy oil and returned to the heating zone. There is a continuous feed of heavy oils to and through the system with withdrawal of light vapors. The vapors pass only in one direction from container 6 to and through container 5 and the liquids pass only in the one direction through container 5 toward and into container 6. The heat of the vapors of heavy oils produced in 6 is taken up by the oil in 5. The oil in 5 is both a scrubbing and a heat-recovering means.

The vapors of the light hydrocarbons pass

through the pipe 23 into a condenser 24 of usual construction which is connected to a gasoline reservoir 25 in the usual manner.

To avoid blowing out oil sludge through the pump 8' valve 26 in pipe 27 may be opened to clear the carbon from container 6 while valves 9 and 10 are closed.

I claim—

1. The process of treating and refining oil for the purpose of transforming heavy hydrocarbon oils into lighter hydrocarbon oils which comprises heating a body of said heavy hydrocarbon oil in a suitable container to a temperature sufficient to develop a pressure not less than 400 pounds per square inch and not greater than 1000 pounds per square inch, passing the evolved vapors over and in contact with a sufficient body of heavy hydrocarbon oil to separate the heavy hydrocarbons in the vapor phase from the light hydrocarbons, the said body of heavy hydrocarbon oil being maintained under the same pressure as that prevailing in the first mentioned body of oil but being at a temperature somewhat less, and continuously supplying fresh oil to said second body and passing oil from said second body to said first body.

2. The process of treating and refining oil for the purpose of transforming heavy hydrocarbon oils into lighter hydrocarbon oils which comprises heating a body of said heavy hydrocarbon oil in a suitable container to a temperature not less than 300° C. and not more than 450° C. and under a pressure to develop vapor of not less than 400 pounds per square inch and not more than 1000 pounds per square inch; passing the evolved vapors over and in contact with a sufficient body of heavy hydrocarbon oil to separate the heavy hydrocarbons in the vapor phase from the light hydrocarbons, the said body of heavy hydrocarbon oil being maintained under the same pressure as that prevailing in the first mentioned body of oil but being at a temperature somewhat less, and continuously supplying fresh oil to said second body and passing oil from said second body to said first body.

3. The process of treating heavy petroleum oil which comprises establishing and maintaining a body of heated heavy oil at a temperature between 300° C. and 450° C. and under a pressure between 400 pounds and 1,000 pounds per square inch, continuously supplying heated oil to such body from a second body of oil under the same pressure but at a less temperature, removing the vapors from the first mentioned body of oil, transmitting them over the second body of oil and then condensing, there being a feed of fresh heavy oil to the second stated body and thence to the first stated body in proportion to the disappearance of oil due to the formation of such vapors and a sufficient withdrawal of oil sludge to prevent excessive deposition of carbon.

4. The process of treating heavy petroleum oil which comprises establishing and maintaining a body of heated heavy oil at a temperature between 300° C. and 450° C. and under a pressure between 400 pounds and 1000 pounds per square inch, continuously supplying heated oil to such body from a second body of oil under the same pressure but at a less temperature, removing the vapors from the first mentioned body of oil, transmitting them over the second body of oil and then condensing, there being a feed of fresh heavy oil to the second stated body and thence to the first stated body in proportion to the disappearance of oil due to the formation of such vapors.

5. The process of treating heavy petroleum oil which comprises establishing and maintaining a body of heated heavy oil at a temperature between 300° C. and 450° C. and under a pressure between 400 pounds and 1,000 pounds per square inch, continuously supplying heated oil to such body from a second body of oil under the same pressure but at a less temperature, removing the vapors from the first mentioned body of oil, transmitting them over the second body of oil and then condensing, there being a feed of fresh heavy oil to the second stated body and thence to the first stated body in proportion to the disappearance of oil due to the formation of such vapors and the pressure prevailing in the two bodies of oil also prevailing in the condensing means for such vapors.

6. The process of producing light petroleum hydrocarbons from heavy petroleum hydrocarbons which consists in heating a body of the heavy hydrocarbons in a suitable container to a temperature not exceeding 450° C., passing the gases and vapors of the light hydrocarbons on their course to a condenser over and in contact with a second body of heavy hydrocarbons which serves as a supply for the first body, maintaining on both bodies a pressure of the developed hydrocarbon gases and vapors equal to or greater than their normal vapor pressure in equilibrium with the liquid phase at the temperature of the oil at the point of issuance into the condenser, supplying fresh oil to the second body of hydrocarbons equal to the combined withdrawal of vapors from the second body and carboniferous oil from the first body.

ROY CROSS.
